UNITED STATES PATENT OFFICE

FRED RICKS, OF LEICESTER, ENGLAND, ASSIGNOR TO UNITED SHOE MACHINERY CORPORATION, OF PATERSON, NEW JERSEY, A CORPORATION OF NEW JERSEY

WAX-THREAD SEWING MACHINE OR OTHER MACHINE EMPLOYING WAX OR LIKE HEATING DEVICES

Application filed October 29, 1925, Serial No. 65,593, and in Great Britain December 18, 1924.

This invention concerns wax thread sewing machines or other machines (such as heel finishing machines) employing wax (or like) heating devices and is more particularly concerned with that type of such machines in which not only is wax or the like (hereinafter referred to as wax) heated in a container but in which also an operating instrumentality (such as a shuttle, looper, take-up or thread tension or a wax-applying roll of a heel finishing machine) is heated and it is to this type that reference is made hereinafter by the phrase "a machine of the type specified".

In sewing machines employing a wax thread the latter is usually passed through a receptacle containing melted wax to impregnate it with wax before it is incorporated in the seam. The wax receptacle or pot, even when forming part of the machine, is usually located at a point remote from the working point of the machine and in order to keep the waxed thread in proper condition until it reaches the work machines of this class are as a rule provided with a heating system arranged to heat the parts of the machine adjacent to and engaged by the thread as it passes towards the working point.

For instance, in curved-hook-needle wax-thread sewing machines the thread is laid in the hook of the needle by a looper which carries the thread about the needle, and it is desirable that this looper should be heated to prevent the chilling of the wax thread as it passes from the take-up through the eye of the looper on its way to the work. It is also desirable that the take-up and the thread tension devices which are usual in such machines should be heated, and it has been customary to heat these parts by means of pipes carrying steam and located adjacent to the parts so that the latter shall be adequately heated. It being necessary also to get the wax in the waxpot in a melted state it has been customary to pass the pipe carrying the steam through the waxpot, or the waxpot jacket if there be such, on its way to the said parts.

The use of steam has been found to be fairly satisfactory where there is normally in the factory a supply, but where this is not

available and it has to be generated at the machine the cost is somewhat high. As it is desirable to work with it at about 60 pounds pressure per square inch, such generation involves a somewhat expensive generator and in order to keep the capital cost of this generator as low as possible it has been usual to make it comparatively small, with the result that it is necessary that the machine be shut down two or three times a day to supply water to make up for normal loss. It is proposed to use oil as the heating medium instead of steam, since it is not necessary to heat oil under pressure and consequently no expensive generator is necessary, and oil has the further advantage that it can be heated to a much higher temperature than water or even than steam at suitable pressure. Another advantage of oil is that it circulates better than steam under certain conditions.

An illustrative embodiment of the invention will now be described in detail and purely by way of example as applied to a curved hook needle inseam sewing machine of the type described in the patent to Eppler No. 1,108,560, dated August 25, 1914, reference being made to the accompanying drawing which is a diagram indicating a method of applying the invention to such a machine.

The machine is provided (as is the machine described in detail in the aforementioned patent) with a curved hook needle, an awl, a thread arm, a looper, a take-up mechanism, and a thread tensioning device, all of which parts have substantially the same construction, arrangement and mode of operation as the corresponding parts of the machine illustrated in the said patent.

Located near the base of the machine is a rotary pump 1 driven by means of a belt (if desired through reduction gearing) from a small pulley connected to the usual fast pulley of the machine so that whenever the factory shafting is running the pump will be in operation. From the delivery end of the pump a pipe 3 is carried upwards to a heater 5 having a chimney 6 where it is coiled as much as is necessary to provide for the proper heating of the oil that it carries. It then passes upwards to a heating element indicated

at 7 for the thread tensioning device which it heats in the usual manner, thereafter passing to heating elements at locations adjacent to the looper indicated at 9 and the take-up indicated at 11 to heat these. The pipe next passes upwards to a reservoir 13 (preferably of glass so that the level of the oil therein can be readily seen) located about the highest point of the machine, and from the reservoir a pipe 15 passes downwards through the waxpot 17, the pipe itself forming the heating element for the waxpot, and thence back to the inlet of the pump.

Adjacent to the reservoir there is a by-pass 21 between the pipes 3 and 15 provided with a cock 23 so that if desired the oil may pass directly from the upflow pipe 3 to the downflow pipe 15 without passing through the reservoir. There is a second by-pass 31 so arranged that the oil that has flowed down through the waxpot 17 may pass direct to the heater 5 without passing through the pump 1, there being an automatically operating valve 33 (for example a ball valve) in this by-pass 31 so arranged that the delivery from the pump when the latter is in operation must pass up through the heater and cannot pass backwards and upwards through the downflow pipe 15. It will be observed that the oil with which the piping system is supplied will pass first to the machine instrumentalities, which being heated indirectly are easily cooled, and thereafter to the waxpot so that the wax is heated by the partially cooled oil, this arrangement being of considerable advantage since wax if overheated is liable to deterioration.

As the partially cooled oil passing through the waxpot may not at all times be sufficiently hot to heat the wax to the desired temperature the chimney 6 of the heater 5 is offset so as to direct the fumes from the heater against a portion of the waxpot 17, the top of the chimney 6 and the adjacent side of the waxpot being preferably so shaped that the heat will be conserved as much as possible. To provide for varying the amount of heat delivered to the waxpot by the chimney the latter is mounted for rotation upon the heater so that it can be turned to direct the fumes either directly on to the waxpot, partially on to the waxpot or completely away from the waxpot. The axis of the oil carrying pipe 3 passing from the chimney 6 is arranged to coincide with the axis of rotation of the chimney so that the pipe passes upwards through one side of the chimney without interfering in any way with the rotation thereof.

The waxpot has been described as being heated by the pipe 15 but it is to be understood that such heating may be effected either directly by the oil piping or indirectly thereby, as for example through the medium of a water jacket. It is to be noted that the size of the oil-carrying pipe should be suitable for the

grade of oil being used, since a thick oil requires a larger pipe than a thin oil if the circulation is to be started with ease. It should be pointed out too that to facilitate the thermosiphonic action bends in the piping are preferably reduced to a minimum and as much of the piping as possible is disposed in rectilinear vertical lengths; in the illustrative construction this has been done notably so in the case of those lengths respectively rising from the heater and descending through the wax back to the pump and heater.

The invention having been described, what is claimed is:

1. Heating apparatus for machines of the type specified comprising a pipe system having an instrumentality heating element and a waxpot heating element, liquid in the pipes, a heater for the liquid, and waxpot heating means in addition to said waxpot heating element.

2. Heating apparatus for machines of the type specified comprising a pipe system having an instrumentality heating element and a waxpot heating element, liquid in the pipes, and a heater for the liquid arranged to supply heat to the waxpot in addition to that supplied by the waxpot heating element.

3. Heating apparatus for machines of the type specified comprising a pipe system having an instrumentality heating element and a waxpot heating element, liquid in the pipes, and a heater for the liquid provided with a chimney to direct fumes from the heater against a portion of the waxpot.

In testimony whereof I have signed my name to this specification.

FRED RICKS.
